Stephen A. Long. U. S. Survey 7915 1/2 X

Letter Patent

The schedule referred to in this Letter patent and making
part of the same containing a description in the words of the said
Stephen A. Long himself of his improvement in the construction
of steam steam-boilers, of locomotive and other steam engines, & the
boiler-pump of such engines and the wharf for locomotive engines

To all to whom these presents shall come
Be it known that S. Stephen A. Long of the United States
having invented and adopted certain novel and useful improvements
in the construction of the main Steam-boilers of the Power
of Locomotives and other Steam engines. Also in the con-
struction of the fore-pump of such engines. And also in the con-
struction of the wharf for Locomotive Engines and of other
locomotives and that the following is a full and exact
description of my said improvement. Be it

First. Of the main Steam-boiler.

My improvement in the steam-boiler consists in the adoption
of two valves on about the boiler which I designate the upper
and lower valves and which in conjunction disseminate
the double side valve. The object of the upper valve is to inter-
fere with the passage of the steam from the cylinder at about
half of any stroke of the piston while that of the lower
valve is to regulate the admission of steam after
the upper valve has closed the cylinder.

It is a departure from the ordinary double valve in having
the upper valve placed all the time on the admission of
steam and the lower valve placed on the admission of steam
so as to be always in the admission of steam.

1953

into them, or vice versa, with the passing through the upper surface of the lower value. The surface last mentioned is of equal area to the remainder of the value, with the rest of the value, that is to say, an aggregate area equal to that of either surface situated in the lower side of the value or in the value itself, when there are two surfaces on either side of the centre of the value, and in its upper side from the area of each should be equal to one-half that of the lower surface, and when there are three surfaces in the upper surface, the area of each should be equal to one-third that of the lower surface, and in a similar proportion for a greater number of surfaces, all the surfaces leading through the lower value from its centre to the upper side of the cylinder. The lower value also differs from the common value in the manner of its attachment to the value, for which is effected by means of a single bolt which serves not only to connect the value to the rod, but to adjust the value in its proper position. It moreover differs from the common value in being furnished with guides to regulate the movement of the upper value. The upper value is furnished with one or more perforations in each side of its value, corresponding to the surfaces on the upper side of the lower value, and respectively of equal area, the number being less by one than that of the lower value, on each side of its centre, the centre being between the surfaces of the upper and lower values, so that the upper value is unassisted by the upper side of the lower value, the surfaces on the other side are assisted by the upper value and vice versa.

The attachment sprung and closing of the surfaces of the lower value is effected by a bolt passing through the movement of the upper value and unfastening the bolt, and the value is then held in its proper position by the bolt passing through the movement of the upper value and the bolt passing through the surfaces of the lower value.

the distance traversed by the lower valve and when this is done
over, the motion of the upper valve should be given with the time
of the lower valve due proportion for any other number of valves
(the means of adjusting the high and lower valves and of intro-
ducing the passage of the steam into the cylinders at about half
the stroke of the piston will be more clearly understood by an in-
spection of the drawings ~~here~~ to be annexed.

Second. Of the force Pump.

My method of constructing and adjusting the valves of the Force Pump for Pneumatic and other Steam Engines consists in the introduction of two or more valves through which the water is forced from the pump to the Boiler, and two other similar valves through which the water is drawn into the Pump, all of which valves are arranged one above another and at suitable intervals around in one and the same valve - box or chamber which may be either of a cylindrical form or of the form of a Parallelotripectad. The latter being deemed most convenient.

The two draft valves occupy the lower while the free valves occupy the upper portion of the valve chamber. The base of the free valves in which the plunger or piston operates and which may be of any convenient form communicates with the valve chamber at a point and through an orifice situated between the draft and the free valves.

The portion of the cubic chamber which is situated between the two draft valves has an outlet in one of its sides, communicating with a hand pump to be worked occasionally by manual labor for the purpose of supplying the tanks when the engine is stopped. It is all built in red iron.

21/11/1963. 0500 hrs. into the salar chamber and thence into the first
troughs on either side of the lower extremity of the chamber and
then into the upper troughs on the upper extremity of the chamber.

in a manner to prevent all leakage - The entire front of the
cubic chamber except a small moulding at the top and bot-
tom is covered by three lids, either of all of which may be removed
and replaced at pleasure by means of the screws bolts which
confine them to the chamber - The form of the chamber may
be cylindrical or square as may be found most convenient
The square form is however deemed preferable inasmuch as it
affords greater facility for the insertion of the valves and for the
adjustment of the lids or covers

Third of the Wheels

In addition to former improvements in the construction of the
Wheels of the Pennsylvania Railroad. I claim as a new
and useful improvement in the construction of Locomotive Engines
the application of circular iron hubs cast in a single piece each
for the reception of wooden spokes. Said hubs being constructed
after the manner heretofore adopted by McSmiley of Philadel-
phia in the construction of business and passenger cars

I also claim as a new and useful improvement in the
construction of Car Wheels and especially of the Wheels of Locomo-
tive Engines the adoption and use of double felloes of wood. in
connection with Cast iron hubs and wooden Spokes

The wheel rim is composed of two distinct series of half-fel-
loes applied to the spokes by means of notches in each series con-
facing the tenons of the spokes instead of mortises. The felloes are
arranged in such a manner that the half-felloes of one series
break joints with those of the other series. By this means the
screws of connecting the felloes together is obviated although
screws either square or round may be employed if desired.
The double felloes are firmly bonded together by nuts, placing them
there near to and on both sides of every spoke. In applying the
wheel rim to the wheel rim the construction here should be taken
to avoid breaking the felloes which may be caused by the
felloes being struck by a nail or the like.

and to impart additional strength and stability to the wheel. I employ iron clamps situated between the felloes and the tire at three points where the ends of the felloes are united and where of course the hub-cam is weakest. These clamps are applied transversely of the wheel, and extend quite across the felloes. - Each clamp is composed of a bar of iron about half an inch thick and about one and a half inches wide and is furnished with a half head or joggle at each end of a depth equal to that of the bar and formed by bending the ends of the bar at right angles with itself. - The heads of the clamps are adapted to rest on the felloes prepared for their reception, while the intermediate parts of the clamps lie embedded in the felloes and in immediate contact with the tire. The nail or bolt by which the bar is fastened upon the iron passes through the clamp, which is furnished with holes for their reception.

The numbered drawings and their explanations, will exhibit more clearly the ~~the~~ nature of the principal improvements described and the manner of their application.

Explanations of the Drawings

Fig 1. A vertical section of the double-cylinder and its ^{top} ~~top~~ with a portion of the steam chest.

A a part of the Steam Chest - B the valve-seat

a portion of the side-pipes communicating with the steam cylinder - b the steam pipe for admitting the cylinder to

the exhaust pipe - C the lower side-pipe valve

C the steam pipes leading through the valve each way communicating with a single valve in the lower side-pipe of the valve and with three valves on its upper side face

D valve upper side valve communicating with the lower valve by means of the valves A & B. The movement of the upper valve is effected by sliding in the upper surface of the lower valve body

and of part of the steam pipe through the latter alternately

Fig. 3. a vertical section of the lower slide valve stem as C. c. 2 of Fig. 1.

Fig. 4. a horizontal view of the steam valve seat stem as E. a. 2. of Fig. 1.

Fig. 5. a horizontal view of the lower surface of the lower slide valve.

Fig. 6. a horizontal view of the upper surface of lower steam valve C. c. 6. of Fig. 1. 45 mm. as in Fig. 1.72.

Fig. 6. a horizontal view of the upper steam valve stem as D. d. of Fig. 1. c. Arms projecting from the valve and impinging against the sides of the valve chest in order to intercept the movements of the valve for the purpose of allowing the lower valve to slide beneath it far enough to close the spaces alternately in each side of the valve chest.

Fig. 7. a vertical section of the valve chamber of the force pump exhibiting the relative positions and arrangement of the valves A. the valve of water. B a branch pipe or pipe communicating with the barrel of the force pump, which has no communication with the valve chamber. C the pipe through which the water is forced into the boiler. D the pipe through which the water is drawn into the valve chamber and pump. E. the pipe communicating with the barrel of the hand pump - a the force water to the draft valve. c. the valve seat.

Fig. 8. a horizontal section of the valve chamber through the tube communicating with the force pump.

A and B same as in Fig. 7.

F. a cap or Bonnet covering one of the apertures of the valve chamber - Fig. 9. a front view of the valve chamber exhibiting the bonnets F by which the apertures of the chamber are closed - Fig. 10. a side view of the valve chamber exhibiting the tube communicating with the hand pump.

A. E. F. same as in Fig. 7. G. H. 8.

Other improvements described in the foregoing specifications.

and claimed as new, useful and original are briefly as follows. The - 1st the construction and application of the dead balance valve and the steam ways, not only the main steam valve of Locomotive Engines but of other Steam Engines in which it is desirable to intercept the passage of the steam into the working cylinder at half or less than half the stroke of the piston - Second - The adoption and construction of a single valve chamber for the fire pump of a Locomotive or other Steam Engine in which chamber all the valves of the fire pump are situated one above another, the number of valves being irrespective of any increase that may be deemed desirable or that there may be one or more draft or suction valves and one or more fire or ejection valves - I now claim as new and useful the mode of connecting the valve chamber with the fire pump, by means of which the water is first drawn into the fire pump, through the lower part of the valve chamber and then forced upward toward the piston through the ^{upper} part of the same valve chamber.

I also claim as new and useful the method of connecting a hand pump to the main valve chamber, which is effected by a communication with the latter at any point situated between any two of the valves - Third, the employment of double guides in the construction of wooden blocks for rail road carriages, of all descriptions and the application of circular blocks of cast iron each hub being formed of a single casting, to Locomotive Steam Engines.

These several improvements, I claim, new especially in their application to Locomotives or other Steam Carriages intended for Rail Roads.

In testimony that the above is a true specification of my said improvements as above described I have hereunto set my hand this twenty sixth day of August A.D. 1853.

Witnessed,
Charles F. Knobell
